MULTIPLE TUBE BOILER ARRANGEMENT

Oscar A. Yost, New York, N. Y.

Application May 2, 1952, Serial No. 285,600

1 Claim. (Cl. 122—1)

1

This invention relates to a double water tube boiler and more particularly to an arrangement for utilizing the waste heat in the gases leaving the boiler and passing toward the smokestack.

It is an object of the present invention to provide a double boiler arrangement whereby waste heat in the gases leaving the boiler furnace may be utilized for keeping the hot boiler of one of the boilers of the arrangement from the gases passing outwardly of the other boiler of the arrangement whereby the one boiler furnace can be kept hot at all times except when shut down for repairs, and thus oxidation of the fireside of the tubes, stays, braces and furnace shell will be eliminated, because the carbon dioxide content of gases in boilers operating on 450 pound pressure are usually from 5 to 15 percent carbon dioxide and accordingly free of oxygen and wherein the one or dead boiler will be kept at an even temperature of approximately 300 degrees Fahrenheit.

It is another object of the present invention to provide a double boiler arrangement wherein gases from one boiler arrangement having a temperature of 600 degrees Fahrenheit may be easily and conveniently delivered to a dead boiler in which boiler tubes have been emptied of water and to bring these boiler tubes to a temperature of about 600 degrees Fahrenheit so that all scale adhering to the water side of the tubes will be dried to a fine powder and can be easily washed out in the usual manner applicable to washing out of the water side of the boiler and whereby to reduce the cost of maintenance in this manner in the running of steam boilers and to eliminate the need for cleaning the tubes with chemicals, hand cleaning and to thereby prevent damage to gaskets resulting from chemical cleaning and provide means for cleaning the inside of water tubes which have a curvature.

It is another object of the invention to reduce the cleaning cost of water tube boilers so that the operator can do the cleaning himself as a routine operation and to eliminate the methods now in use which are usually done by shipyards at high cost and wherein the boilers will be kept in substantially the same condition as originally when new and wherein there will be a great saving of the total fuel consumption and in the amount of from one to ten percent of the present cost.

Other objects of the invention are to provide a double boiler arrangement wherein the waste heat of gases leaving one boiler may be utilized in the other boiler or reused in the same boiler by a simple manipulation of valve elements, a blower motor and thermostat control, which is of

2

simple construction, easy to install, inexpensive to manufacture, reduces costs of insurance and underwriters' costs, permits idle boilers to be brought up to full planned power output in a short time, reduces the chances of accidents, keeps boilers in ready operation, compact, and efficient in operation.

For other objects and for a better understanding of the invention, reference may be had to the following detailed description taken in connection with the accompanying drawing, in which:

Figure 1 is a vertical sectional view of the double boiler arrangement and the waste gas pipe and valve arrangement embodying the features of the present invention;

Fig. 2 is a diagrammatic view of a series of three boiler arrangements embodying the features of the invention;

Referring now particularly to Fig. 1, 11 and 12 respectively represent two boiler furnaces assembled and arranged to utilize a single smokestack. The furnace 11 has an oil burner 14 for delivering a flame underneath water tubes 15 having headers 16 and 17 at the opposite ends of the same and which is connected by pipes 18 and 19 with an expansion steam and water tank 20. This water tank has a superheater 21 connected to it for the removal of steam by way of fitting 22, steam turbines or other equipment utilizing the steam. A similar arrangement is provided in the other furnace 12 and similar numerals are utilized to designate the similar parts thereof. The products of combustion move upwardly to the top of the furnace and at one point the temperature of these gases may run 600 degrees Fahrenheit and at the level immediately above the superheater. At another level thereabove, the temperature of these gases and products of combustion run about 300 degrees Fahrenheit. The casing of the furnace narrows to provide inclined ducts 24 and 25 which lead to the chimney stack 13.

A blower 26 is attached by a coupling 27 with an electric motor 28 which drives the blower 26 to effect the withdrawal of the hot gases from the steaming boiler. The blower 26 and the electric motor 28 are mounted upon a suitable base 29.

The blower is attached by a vertical riser pipe 31 which is connected to a cross fitting 32. Leading laterally from this cross fitting 32 are valve controlled pipes 33 and 34 which enter the casing of the boiler furnaces at the high temperature level. Baffles 33' and 34' tend to draw these hot gases into the pipes. In the pipe 33 is a valve fitting 35 and in the pipe 34 is a valve fitting 36. These valve fittings can be operated to control

the flow of the gases at the hot gases level to the vertical riser pipe 31 and to the blower 26.

Elevated above the cross fitting 32 and extending therefrom is a vertical extension pipe 37 which has a T-fitting 38 on an upper end and which is connected by pipes 39 and 40 with the boiler furnace casing to remove gases at a reduced temperature of 300 degrees Farenheit therefrom. These pipes respectively have baffles 39' and 40' to direct the gases toward the pipes. The pipe 38 has a valve control element 42 and the pipe 41 has a valve control element 43.

It can be seen that by the operation of the valves 35, 36, 42 or 43 that the gases can be taken off at different elevations and at different temperatures and from the different boiler furnaces.

The hot gases are delivered through the outlet pipe 44 leading from the blower 26 and which is connected to a T-fitting 45 from which pipes 46 and 47 extend. These pipes 46 and 47 respectively lead to fire boxes 48 and 49 of the furnaces 11 and 12. The pipe 46 has a valve control element 51 and the pipe 47 has a valve control element 52. It is thus seen that the supply of the hot gases to either of the boilers 11 and 12 can be effected by the operation of the control valve elements 51 and 52.

As shown in the drawing, the right boiler is in operation while the left boiler is dead. The left boiler may be emptied of water and completely shut down. A thermometer 53 capable of measuring the temperature from 1 to 1,000 degrees Farenheit is provided on the discharge pipe which leads from the blower 26 and indicated at 44. All the piping, the valves and the blower are well insulated so as to retain the heat from the gases taken from the boiler in use.

The size of the pipes can vary according to the horsepower of the boilers. A motor from one-half to one and one-half horsepower of the variable speed type should be used. The blower capacity should conform and balance with the electric motor. The piping valves do not have to be of heavy material, as the gases on large boilers do not exceed ten pounds pressure. This arrangement will be used on water tube type boilers, using fuel oil for firing purposes, and the fired gases should be clear of soot.

To put this system into use so as to heat the end boiler, the blower and the motor are started and all of the valve elements except valve elements 43 and 51 are closed. Valve element 43 and valve element 51 are open. Gases at the 350 degree temperature level will accordingly be taken from the boiler 12 and transferred to the fire box 48 of the boiler 11 to bring up the temperature of the boiler 11 and to keep the same at an even temperature of 300 degrees. It will thus be seen that there is no need to have a cold boiler when out of use, unless repairs have to be done on brick work or furnace registers. By using this arrangement many of the repairs are eliminated. By this means at all times on idle boilers oxidation of the fire side of the tubes, stays, braces and furnace shell will be eliminated as the boilers will be filled with gases having a carbon dioxide content of from 5 to 15 percent and quite free then of oxygen. Accordingly, oxidation is reduced.

This arrangement can be used to clean the water tubing side on the dead boiler. By having the tubing emptied of water and by opening valve 36 and closing valve 43 the temperature from the 600 degree F. level gases will be delivered to the tubing in the boiler 11 to make the temperature

the same to 600 degrees F. so that all scale adhering to the water side of the tubes will dry to a fine powder that can be easily washed out in the usual manner used in the washing out of the water side of a boiler. This operation costs very little compared to the cost of cleaning water side of boilers with chemicals or hand cleaning the turbines. The chemical cleaning can sometimes do a great deal of damage to gaskets and cause leaking tubes. Hand cleaning can only be done on straight tubes and is not satisfactory on superheated tubes due to the curvature of the same. Using this operation on cleaning, labor and material costs are cut or eliminated and the operator can do the cleaning himself as a routine operation and the usual methods now in the marine field are done by shipyards at high cost are thus eliminated. This arrangement will keep the boilers in the same condition as originally when new and will save more than ten percent of the total fuel consumption.

This arrangement can be used to start steam operation on the end boiler. This is effected by filling the tubes to the normal water level and by the use of valves 43 and 51 which will be opened. The temperature will be increased in the boiler 11 and thereafter the valve 36 is partially open to increase the heat; after a few minutes valve 43 is closed so that only the hot 300 degrees F. gases are used. Eventually the idle boiler will be steaming in all parts to an even temperature of 600 degrees F. or at any other temperature as can be regulated by the use of the valves 36 and 43. This is a much better practice of starting up a new boiler than lighting of the fire every few hours or so at a high cost of fuel. By the present arrangement this fuel cost is reduced fifty percent and the original shock to the tubing and brick work of the dead boiler will be nil. Fuel fire runs about 3,000 degrees F. on starting and it is quite a shock to brick work and to the tubing as a result of uneven expansion thereof. Where a slow even heat is provided by the present arrangement, no shock to parts of the boiler is involved. Accordingly, this present arrangement should prolong the life of boilers as much as 25 percent. This arrangement is particularly useful when rebrickling in order to dry out mortars slowly. Insurance and underwriters costs are reduced since all idle boilers are ready for plant power output in shorter time than is now the practice.

It is the usual practice to clean the fire side of tubes with very hot water and as a result thereof the tubing upon being dried shows indications of rust. If the present arrangement is used, hot gases can be transferred from the live boiler to dry off the water on the tubes and thereby prevent the rusting of the same as a result of this cleaning operation.

It will be understood that while the boiler 11 is not indicated as the dead boiler that by the use of valves 35, 42 and 52 that similar operations can be carried out by the use of boiler 11 upon boiler 12.

It will be seen that the blower 26 can be driven by any power which may be available if there is not any electric motor available, such as air, steam or independent drive.

Referring now to Fig. 2, it will be seen that any multiple arrangement of boilers can be used, as shown in this view where three boilers are arranged with parallel connections. The boilers are indicated generally at 55, 56 and 57 and they are constructed similar to the boilers shown

above. Each boiler has a separate stack indicated respectively at 55', 56' and 57'. Each stack has pipes 58 and 59 with valves 60 and 61 respectively. These pipes are at respective upper and lower levels in the furnace. Pipes 58 and 59 lead through to a common pipe 62 which delivers the gases to a blower 63. Leading to each boiler 57, at the firebox level thereof, is a pipe 64 having a valve 65 which leads to a common pipe 66 connected with a discharge side 67 of the blower 63. The electric motor 68 drives the blower 63.

It will be apparent that by a manipulation of the different valves hot gases at the different temperatures and levels can be taken from one or two of the boilers and delivered to the fire box of the dead boiler in order to keep it warm or to start its operation.

It will now be apparent that there has been provided an arrangement which makes for an efficient boiler plant with which great savings of material and labor will be obtained. It will be seen that this arrangement makes it unnecessary for the ship to be put out of use for any great length of time and the boiler plant will be kept in good running order while still in use.

While various changes may be made in the detail construction, it shall be understood that such changes shall be within the spirit and scope of the present invention as defined by the appended claim.

What is claimed is:

A double boiler furnace arrangement comprising two boiler furnaces having respectively water tube boilers therein, a super heater above each boiler and operatively connected with the respec-
